RECEPTACLE

Arnold Perreton, Durham, N. H.

Application January 25, 1936, Serial No. 60,761

6 Claims. (Cl. 229—31)

This invention relates to a receptacle and particularly to a receptacle constructed of folded sheet material that may be collapsed to facilitate the removal of an article or material therefrom.

5 The primary object of the invention is to provide a receptacle of the character mentioned and preferably constructed of moisture resisting paper folded in such a manner that it may be easily and quickly disengaged from the article or substance contained therein, particularly if such article or substance is of a sticky nature and has a tendency to cling thereto.

Another object of the invention is to provide a receptacle formed by folding sheet material and 15 temporarily sealing folded portions thereof in such a manner that in removing the article or substance therefrom the seal may be easily broken and the folded portions unfolded and opened by pulling outwardly in opposite directions upon 20 tabs provided for such purpose.

Still another object of the invention is to provide a receptacle which, upon being unfolded and having an article of food therein, may be placed upon a plate and temporarily secured thereto by 25 means of the previously used sealing material, the unfolded receptacle in effect constituting a tray upon which the food is served.

The invention consists in a receptacle as set forth in the following specification and particularly as pointed out in the claims thereof.

Referring to the drawings:

Fig. 1 is a plan view of a blank from which the receptacle of this invention is formed, the lines upon which the blank is folded in forming 35 the receptacle being illustrated by light dash lines.

Fig. 2 is a perspective view of the receptacle.

Fig. 3 is a perspective view illustrating the receptacle in a partly unfolded or collapsed position.

Fig. 4 is a plan view illustrating the reverse 40 side of a corner portion of the blank from that illustrated in Fig. 1.

Fig. 5 is a plan view similar to Fig. 4, but illustrating an alternate flap structure for the receptacle.

45 Fig. 6 is a plan view similar to Figs. 4 and 5 and illustrating another alternate flap construction.

Fig. 7 is a perspective view illustrating a slightly modified embodiment of the invention.

50 Fig. 8 is a plan view of a blank from which another receptacle embodying the features of my invention may be formed.

Fig. 9 is a perspective view of a receptacle 55 formed from the blank illustrated in Fig. 8.

Like numerals refer to like parts throughout the several views of the drawings.

In the drawings, referring particularly to Figs. 1 to 4 inclusive, 6 represents a blank from which 60 the receptacle of this invention is formed, said

blank consisting of a single piece of sheet material, preferably paper treated to resist moisture and approximately square in outline, but being extended from diagonally opposite corners thereof at 7. The blank 6 is folded upwardly upon the lines 8 to form opposite side walls 9, opposite side walls 10 and a bottom portion 11, and in folding said blank creases are formed at 12 thereby forming folds 13, as illustrated in Fig. 3, which are folded backwardly against the side walls 9 as illustrated in Fig. 2. The diagonally opposite corner portions 7 of the blank 6 are folded at 14 to form downwardly extending flap portions 15, and the latter are folded upwardly at 16 to form pulling tabs 17. Other diagonally opposite corner portions of the blank 6 are folded downwardly at 18 to form pulling tabs 19.

After the blank 6 has been folded upon the lines 8 and 12, and the folds 13 have been folded backwardly against the side walls 9, said folds are held against said walls by the downwardly folded flap portions 15 which are caused to adhere to said folds by a plastic adhesive material 20 located upon the under side of the flap portions 15. Preferably, the adhesive material 20 is of a type that 25 remains both plastic and adhesive indefinitely both before and after it is utilized to secure the folds 13 and flap portions 15, and said material may be applied directly to the under side of said flap portions or, it may be located upon a strip of 30 suitable paper or fabric tape which in turn may be applied to the flap portions. When the folds 13 are secured in folded position against the side walls 9, the folds 13, flap portions 15 and pulling 35 tabs 17 all act to reinforce and stiffen said side walls, while the pulling tabs 19 when folded downwardly against the side walls 10 act to reinforce the upper edge portion of said walls 10.

Arrows 21 may be printed or otherwise applied to the surface of the blank 6, as illustrated, for the purpose of indicating the direction in which the tabs should be pulled.

In Fig. 5 I have illustrated an alternate flap structure in which a reinforcing piece of sheet material 22 is secured to the reverse side of the blank 6 from that illustrated in Fig. 1, at the extensions 7, for the purpose of reinforcing the blank at the fold lines 14, and plastic adhesive material is applied at 23 to said reinforcing material. In this structure the reinforcing pieces 22 will strengthen the structure of the receptacle at the fold lines 14 when the tabs 17 and flap portions 15 are pulled outwardly, particularly if there is a tendency for the article or substance within the receptacle to cling to the side walls thereof.

In Fig. 6 still another alternate flap structure is illustrated in which a flap portion 15 is provided with openings 24, and a strip of sheet material 25, preferably transparent, is applied to said 60

flap portion over said openings. Plastic adhesive material 26 is applied to the sheet material 25 at the openings 24 for the purpose of securing the flap portion to a side wall 9 as hereinbefore set forth.

5 The receptacle of the invention is particularly provided for the purpose of receiving articles and substances of a sticky nature as, for example, comb honey, which has been severed into small pieces and may have a tendency to cling thereto and be difficult to remove therefrom. In removing such substances as honey from the receptacle the tabs 17 are first pulled outwardly in opposite directions thereby exerting a pull upon the flap portions 15 and disengaging the latter from the folds 13 where they are secured together by the adhesive material 20 or 23, and a continued outward pull will separate the side walls 9 from the honey and open the folds 13. The flap portions 19 are then pulled outwardly thereby separating the walls 10 from the honey.

A satisfactory method of serving comb honey is to allow said honey to remain upon the collapsed receptacle and attach the latter to a plate 25 in which event the opened receptacle in effect constitutes a shallow tray. Under such circumstances the tabs 17 and flap portions 15 are folded beneath the rim of the plate and attached to the underside thereof by means of the adhesive 20 or 23 which still retains its adhesive qualities.

If the article within the receptacle does not stick thereto, said receptacle will collapse satisfactorily by pulling on the tabs 17 only.

35 In Fig. 7 I have illustrated a modified embodiment of my invention wherein a receptacle is provided with downwardly tapering opposite side walls 27 and 28 thereby making it possible for a plurality of said receptacles to be nested one within another. In this structure opposite side walls 27 are provided with folds 29, flap portions 30 and pulling tabs 31, and opposite side walls 28 with pulling tabs 32, all similar to corresponding portions of the receptacle illustrated in Figs 1 to 4 inclusive and functioning in exactly the same manner.

In Figs. 8 and 9 still another modified embodiment of the invention is illustrated wherein a blank 33 consisting of a single piece of sheet 50 material, preferably waterproofed is formed into an eight sided open receptacle. The blank 33 is creased and folded upon the light dash lines as indicated in Fig. 8 to form a plurality of side walls 34, a plurality of other side walls 35 and 55 a plurality of folds 36. The folds 36 are folded backwardly against the side walls 34 and secured thereagainst by flap portions 37 which are folded downwardly from the top edges of the side walls 34 against said folds and against said side walls 60 as illustrated in Fig. 9. The flap portions 37 are secured to the folds 36 by a plastic adhesive material of the type previously mentioned which is applied at 38 to the rear side of the flap portions, and the latter terminates in upwardly 65 folded pulling tabs 39. Pulling tabs 40 are folded downwardly from the top edges of the side walls 35.

The receptacles of Figs. 7 and 9 may be used 70 as containers for various food products or substances which may have a tendency to cling or stick thereto, and the sheet material of said receptacle may be disengaged from said food products or substances by pulling outwardly in

opposite directions upon oppositely disposed pulling tabs in exactly the same manner as hereinbefore described in connection with the structure illustrated in Figs. 1 to 4 inclusive.

I claim:

1. A receptacle formed of sheet material folded to provide side walls and a bottom portion, opposite side walls having downwardly folded pulling tabs embodied therein, and other opposite side walls having portions folded outwardly and downwardly therefrom and terminating in upwardly folded pulling tabs, and means to temporarily seal said downwardly folded portions to the side walls adjacent thereto, said seal being broken and said sheet material being unfolded by pulling outwardly in opposite directions upon said tabs.

2. A receptacle formed of a single piece of sheet material folded to provide side walls and a bottom portion, opposite side walls having pulling tabs folded outwardly and downwardly therefrom, and other opposite side walls having portions folded outwardly and downwardly therefrom and terminating in outwardly and upwardly extending pulling tabs.

3. A receptacle formed of a single piece of sheet material folded to provide side walls and a bottom portion, opposite side walls having pulling tabs folded outwardly and downwardly therefrom, other opposite side walls having portions folded outwardly and downwardly therefrom and terminating in outwardly and upwardly extending pulling tabs, and an adhesive for securing said last-mentioned downwardly folded portions to the adjacent side walls.

4. A receptacle formed of a single piece of sheet material folded to provide side walls and a bottom portion, opposite side walls having pulling tabs folded outwardly and downwardly therefrom, other opposite side walls having flap portions folded outwardly and downwardly therefrom and terminating in outwardly and upwardly extending pulling tabs, and a plastic adhesive material temporarily sealing said flap portions against adjacent side walls whereby a pull in opposite directions upon said last-named tabs will unfold the sheet material and thereby collapse said receptacle.

5. A receptacle formed of a single piece of sheet material folded to provide side walls and a bottom portion, opposite side walls having pulling tabs folded outwardly and downwardly therefrom, other opposite side walls having flap portions folded outwardly and downwardly therefrom and terminating in outwardly and upwardly extending pulling tabs, folds extending from corners of said receptacle between said flap portions and the adjacent side walls, and a relatively permanent plastic adhesive material temporarily securing said flap portions to said folds whereby a pull in opposite directions upon said last named tabs will unfold the sheet material and thereby collapse said receptacle.

6. A receptacle formed of sheet material folded to provide side walls and a bottom portion, opposite side walls tapering downwardly and having pulling tabs folded outwardly and downwardly therefrom, and other opposite side walls also tapering downwardly and having portions folded outwardly and downwardly therefrom and terminating in outwardly and upwardly extending pulling tabs.

ARNOLD PERRETON.
